Patented Dec. 5, 1916.

UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

MACHINE FOR MAKING STEREOTYPE PRINTING-PLATES.

1,207,674.

Specification of Letters Patent.

Patented Dec. 5, 1916.

Application filed August 11, 1910. Serial No. 576,721.

To all whom it may concern:

Be it known that I, HENRY A. WISE Wood, a citizen of the United States, residing at New York, in the county of New York and State of New York, have invented a new and useful Machine for Making Stereotype Printing-Plates, of which the following is a specification.

This invention relates to a machine for 10 finishing stereotype printing plates, and particularly for shaving them.

The principal objects of the invention are to provide a simple and efficient mechanism for shaving the plates one after the other, 15 operating in such a way that the plates can be shaved as they are moved directly from the casting box on a support, and to so arrange and construct the shaving means that there will be no buckling of the plate while 20 being shaved, and consequently no mechanism will be required for preventing such buckling of the plate; also to provide for conveniently and expeditiously trimming the edges of the plate if desired while it is being 25 transferred to the shaving device.

Further objects and advantages of the invention will appear hereinafter.

Reference is to be had to the accompanying drawings, in which—

Figure 1 is a plan of a portion of a flat stereotype printing plate finishing machine constructed in accordance with this invention; Fig. 2 is a side view thereof; Fig. 3 is a side view of a modification, and Fig. 4 is a bottom plan view of a plate.

In the form of the invention illustrated, the plates A are cast in a casting box 10 which constitutes means for holding a cast plate and moved therefrom by any desired means in a plane on supports 11. This support is on the same level as the holding means 10 when the plate is removed from it. A pair of reciprocating bars 12 operated in any desired way are shown. Each of 45 these arms or bars 12 is provided with a pivot pin 13 on which is pivotally mounted a finger 14 having a hook 15 on the end having a slanting top and adapted to engage in a notch in the underside of the cast plate. A spring 16 holds the hook yieldingly in position for engaging the plate so that upon the reverse motion of the sliding arm 12 the plate will be drawn out of the casting box longitudinally. The plate is

drawn on a set of supports 11 certain of which are bifurcated to permit the hooks to pass between them. These supports are laterally adjustable along a cross rod 17. As the hooks draw the plates out of the casting box the plates are brought against edge trimming saws 20, and their edges are thus trimmed off. These saws are operated by a belt driven in any desired way passing over a pulley 21. If desired these saws can be entirely omitted as shown in Fig. 3. 65 Whether or not these edge trimming saws are present the plates are shaved as they are drawn out by the hooks but while they are firmly supported on the supports 11. This is done by means of a rotary shaver 25 mounted on a shaft 26 on which is a pulley 27 operated by a belt from any desired source of power. It will be observed that as the plate passes under this rotary shaver it is firmly held by the hooks and rests on the 70 supports. Therefore there is no danger of the plate buckling, and no means has to be provided for avoiding this difficulty. The surface speed of the rotary shaver preferably is materially greater than the surface 75 speed of the plate which travels under it. After the plate has been shaved in this way the hooks continue to draw it out until the entire plate passes the shaver when the hooks bring up against stops 28. At this time 80 second carrier pushers 30 mounted on a transversely reciprocating rod 31 move transversely over the supports 11 and engage the plate so as to push it off the supports on a series of slats 32 which are arranged transversely to the supports 11. The hooks 15 are automatically disengaged from the notches in the plate. The hooks engaging in the long slot a are disengaged therefrom at its end when the plate moves beyond them. As soon 85 as the pushers 30 reach the delivery side of the supports 11 they start back and leave the plate in position for further operations. When they have moved all the way back the hooks 15 have moved forward and are 90 ready to start back with another plate. It will be seen that this construction is very simple, that the plates can be efficiently shaved, and that if the plates are cast sufficiently true on the edges so that the edges 95 do not have to be shaved even the saws 20 can be eliminated as shown in Fig. 3.

While I have illustrated and described

two preferred embodiments of the invention, I am aware that many modifications can be made therein by any person skilled in the art without departing from the scope of the invention as expressed in the claims. Therefore, I do not wish to be limited to all the details of construction herein shown and described, but

What I do claim is:—

- 10 1. In a machine for finishing stereotype printing plates, the combination with a support and a shaving device located in position to shave the plate as it is moved on the support, of a set of pushers arranged to move transversely to remove the plate from the support in a line at right angles to its direction of motion past the rotary shaving device.
- 20 2. In a machine for finishing stereotype printing plates, the combination of a rotary shaving device in position to shave one side of a plate while it is being moved along in a plane, and reciprocable spring-pressed hooks for engaging the other side of the plate near its forward edge and drawing it past said shaving device.
- 25 3. In a machine for finishing stereotype printing plates, the combination of means for supporting a wide, thin stereotype plate in the position in which it is discharged from a holding means, edge beveling saws located at the receiving side of said supporting means, a rotary shaving device located above said supporting means in position to shave the plate as it is moved thereon, and means located beyond the shaving device adapted to extend under the shaving device

for engaging the plate and drawing it under the shaving device.

4. In a machine for finishing stereotype printing plates, the combination with a support and a rotary shaving device located above said support in position to shave the plate as it is moved on the support, of means at one side of said support on a level therewith for moving the plate laterally from said support.

5. In a machine for finishing stereotype printing plates, the combination with a support and a rotary shaving device located above said support in position to shave the plate as it is moved thereon, of a set of pushers arranged to move transversely over said support to remove the plate therefrom in a line at right angles to its direction of motion under the rotary shaving device, and means at the side of said support for receiving the plate.

6. In a machine for finishing stereotype printing plates, the combination with a support and a rotary shaving device located above said support in position to shave the plate as it is moved thereon, of a set of pushers arranged to move transversely over said support to remove the plate therefrom in a line at right angles to its direction of motion under the rotary shaving device.

In testimony whereof I have hereunto set my hand, in the presence of two subscribing witnesses.

HENRY A. WISE WOOD.
